GOLF BALL WINDING MACHINE

Norman Ashcroft Hurst, Liverpool, and Desmond Lawson Jenkins, Kirby, England, assignors to Dunlop Tire and Rubber Corporation, Buffalo, N. Y., a corporation of New York

Application September 19, 1955, Serial No. 535,175

3 Claims. (Cl. 242—3)

Our invention relates to golf ball core winding machines. In prior constructions the rollers, upon which a golf ball core was supported during winding, were rotated and simultaneously axially oscillated in order to obtain an even and spherically wound core. The axial oscillation was effected by means of a cam drive. On account of the speed of oscillation of the rollers and the severity of the operating conditions, the cam created a considerable amount of noise which had an undesirable effect upon the operator. This effect was magnified when, as is usually the case, the machines were installed in groups.

Our invention provides an improved golf ball winding machine.

According to the present invention, a golf ball core winding machine comprises a support for a reel or the like of rubber core-winding thread, means for tensioning the thread during winding, a pair of substantially cylindrical core-supporting rollers rotatably mounted in spaced relationship to each other on substantially parallel axes, a pair of freely rotatable concave-profiled rollers mounted in spaced relationship to each other on axes substantially parallel to those of the cylindrical rollers and mounted adjacent to and urged towards the cylindrical rollers, said concave-profiled rollers being movable away from the cylindrical rollers by increase in size of the core during winding, means for rotating the cylindrical rollers, and an eccentric mechanism and associated linkage for axially oscillating each cylindrical roller.

The eccentric mechanism may comprise an eccentric sheave surrounded by a strap within which the sheave is rotatable and the associated linkage may comprise an eccentric rod attached at one end to the strap and at the other end to a rocker itself attached by means of a further link to a cap within which an end of a shaft carrying the cylindrical roller is freely rotatable.

Alternatively, the eccentric mechanism may comprise the crank pin of a crankshaft and an associated bearing within which the crank pin is rotatable.

In one construction of the present invention the cylindrical and concave-profile rollers are rubber-covered and the tensioning apparatus comprises a rubber belt which is supported in a tensioned elongated loop on a pair of stationary, spaced-apart pins. The rubber thread is pressed, during its passage over a freely rotatable pulley, against one side of the rubber belt which is caused to rotate against the frictional resistance of the stationary pins. Means are provided for adjusting the belt to vary the amount of tension imparted to the thread during winding.

The apparatus of the present invention may also comprise means for varying the pressure of the concave-profiled rollers upon a core during winding so as to compact the core as the winding progresses and electrical means may be provided for stopping winding in the event of a break in the core-winding thread and for stopping the winding when the core reaches a predetermined size.

One embodiment of the invention is illustrated, by way of example, in the accompanying drawings in which—

Fig. 1 is a front perspective view of a single golf ball

core winding unit partly cut away and sectioned to show the operating and driving mechanisms;

Fig. 2 is a similar perspective view of the same from the rear;

Fig. 3 is a front elevation of the winding unit;

Fig. 4 is a vertical section on the line IV—IV of Fig. 3.

Conveniently, eight such units are arranged, four on each side, of a supporting framework to form a complete machine.

- 10 The golf ball winding machine unit comprises a pair of cylindrical core-supporting rollers 10 mounted on parallel shafts 11. The peripheral surface of the rollers is covered with a layer of rubber 12 which forms a gripping surface for the rollers during winding of a golf ball core as will be appreciated as the description proceeds. Each shaft 11 is supported in a bearing 13 provided in a face-plate 14 and a second bearing 15 mounted in a supporting framework 16 rigidly attached to the face-plate, the roller shafts 11 being slidable and rotatable in these bearings in a manner now to be described.
- 15 Rotation of the roller shafts is effected by a 45° helical gear 17 mounted on each of the roller shafts 11 between the bearings 13 and 15 and mating with a corresponding helical gear 18 mounted on a drive shaft 19 located above and at right angles to the roller shaft 11. The drive shaft 19 is rotated by means of a pulley 20 (see Fig. 2) attached to an end of the shaft 19 which projects through the side of the supporting framework 16, the pulley 20 being driven by a V-belt itself driven by an electric motor (not shown). One motor is provided for each unit.

- 20 A pair of eccentric sheaves 21 are mounted on the drive shaft 19, each of the sheaves being enclosed by a strap 22 which is directly connected to one end of an eccentric rod 23, the other end of which is pivotally attached to one arm 24a of a rocker 24, freely rotatable on a rocker shaft 25 mounted in bearings 26 carried by the supporting framework 16. Each of the rockers 24 is connected, by means of a second arm 24b formed thereon, to a roller shaft 11 by means of a link 27 and cap 28. Each of the caps 28 carries a pair of roller bearings 28a which are secured to the end of a roller shaft 11 so that, whereas the roller shafts 11 are freely rotatable within the caps 28, the shafts can in addition be axially oscillated by means of the eccentric sheaves 21 through the linkages described and the caps 28 attached to the shaft ends. The eccentric sheaves 21 are relatively positioned on the drive shaft 19 so that the roller shafts 11 and thus the rollers 10 are oscillated out of phase, that is, when one cylindrical roller is approaching its axially innermost position relative to the face-plate 14, the other cylindrical roller is approaching its axially outermost position relative to the face-plate.

- 25 The eccentric mechanism may comprise an eccentric sheave surrounded by a strap within which the sheave is rotatable and the associated linkage may comprise an eccentric rod attached at one end to the strap and at the other end to a rocker itself attached by means of a further link to a cap within which an end of a shaft carrying the cylindrical roller is freely rotatable.
- 30 Alternatively, the eccentric mechanism may comprise the crank pin of a crankshaft and an associated bearing within which the crank pin is rotatable.

- 35 In one construction of the present invention the cylindrical and concave-profile rollers are rubber-covered and the tensioning apparatus comprises a rubber belt which is supported in a tensioned elongated loop on a pair of stationary, spaced-apart pins. The rubber thread is pressed, during its passage over a freely rotatable pulley, against one side of the rubber belt which is caused to rotate against the frictional resistance of the stationary pins. Means are provided for adjusting the belt to vary the amount of tension imparted to the thread during winding.
- 40 The apparatus of the present invention may also comprise means for varying the pressure of the concave-profiled rollers upon a core during winding so as to compact the core as the winding progresses and electrical means may be provided for stopping winding in the event of a break in the core-winding thread and for stopping the winding when the core reaches a predetermined size.
- 45 One embodiment of the invention is illustrated, by way of example, in the accompanying drawings in which—
- 50 Fig. 1 is a front perspective view of a single golf ball
- 55 core winding unit partly cut away and sectioned to show the operating and driving mechanisms;
- 60 Fig. 2 is a similar perspective view of the same from the rear;
- 65 Fig. 3 is a front elevation of the winding unit;
- 70 Fig. 4 is a vertical section on the line IV—IV of Fig. 3.

ports 38, 39 (see Fig. 4) communicate with the cylinder interior so that air pressure may be applied, as desired, to the upper or lower face of the piston so as to cause upward or downward movement thereof.

A manually operated air valve 40 is attached to the back of the face-plate in a position such that a push-button 41 for operating the valve projects through the face-plate. The valve body has an inlet, to which a copper air supply pipe 42 is attached, the inlet being normally closed by a bearing ball (not shown) which is thrust by air pressure within the supply pipe and by light spring against a seating provided in the valve body. A pipe 43 is connected in the side of the valve body. A plunger (not shown) which is slidable in the valve body, carries the push-button 41 at one end, its other end being locatable with the bearing ball so as to lift it from the seating against the pressure on the ball, when the button is depressed, and allow air under pressure to flow from the inlet pipe into the valve body. The air then flows through the pipe 43 to a relief valve 44.

The relief valve 44, Fig. 4, comprises a body portion having a bore 45 within which a shuttle 46 may oscillate. The shuttle is urged by spring 47 towards the lower end of the body which has an inlet connected by pipe 43 (see Fig. 2) with the manually-operated air valve outlet. A relief valve outlet 49 is connected by means of a pipe 50 to the cylinder port 39 communicating with the lower face of the piston. An exhaust port 48 communicates with the atmosphere. The upper end of the relief valve body is provided with a port 51 which directly communicates with the port 38 provided in the cylinder 34. The upper end of the valve body is also connected by means of a pipe 52 to an automatically-operated air valve 53, Figs. 2 and 3, now to be described.

The automatically-operated air valve is attached to the supporting framework 16 and comprises a housing 53 having a bore (not shown) one end of which is provided with a seating upon which a bearing ball is normally held by means of a light spring, so as to close the supply of air from a pipe 55. An outlet 54, connected through pipe 52 to the upper end of the relief valve, is provided at the other end of the bore. A plunger 56 is slidable within the bore so as to depress the bearing ball clear of the seating so that air may flow through the bore of the housing and the outlet 54 to the relief valve 44. One end of the plunger projects clear of the housing and engages a rocker arm 57. The rocker arm is rigidly attached to a shaft 58 rotatable in a pair of bearing lugs 59 formed integrally with the housing. One end of the rocker shaft 58 projects beyond one of the lugs and is rigidly connected to rocker arm 60 which is also connected by means of a link 61 to a crank pin 62 attached to one face of a gear wheel 63 which is driven by a pinion 64 rigidly attached to the end of the drive shaft 19 remote from the pulley 20. The gear ratio between the pinion and gear wheel is such that for every ten rotations of the pinion and drive shaft the automatic valve is operated through the link and rocker arms once only.

When the automatically-operated valve 53 is operated, air is caused to flow therefrom to the relief valve 44, the shuttle 46 being unaffected thereby and remaining at the lower end of the relief valve body, the air flows from the relief valve through the port 51 into the cylinder and against the upper face of the piston to urge it downwardly in the cylinder whereby the concave-profiled rollers 29 are forced against a golf ball core during winding in order to compact the rubber thread 90 thereon as will be more readily appreciated as the description proceeds.

A thread-tensioning device 65 is attached to the face-plate 14 on one side of the cylinder 34 and comprises a freely rotatable tensioning pulley 66 mounted on a horizontal axis and a pair of freely rotatable guide pulleys 67 mounted adjacent to the tensioning pulley

so that rubber thread 90 may pass from a reel 91 supported on the face-plate 14 first around one of the guide pulleys 67, then the tensioning pulley 66 and then around the other guide pulley 67. It then travels over a pulley 68 associated with a thread-break indicated device, later to be described, and around a core located between the rollers.

A rubber belt 69 is supported in a tensioned elongated loop on a pair of stationary, spaced-apart pins 70, 71 adjacent to the tensioning pulley. The lower flight of the rubber belt is deflected by the outer periphery of the tensioning pulley so that it contacts the tensioning pulley along a portion of its outer periphery which subtends at the pulley centre an angle of about 20°. The pins around which the belt passes are carried on brackets 72, 73 one of which (73) is slidable on a back plate 74 towards and away from the other so as to increase the belt tension by means of a thumb screw 75 attached to the bracket and bearing upon a portion of the back plate. The other bracket 72 is slidable on the back plate in a vertical direction so as to increase or decrease the amount of belt lap upon the tensioning pulley.

When the thread 90 passes over the tensioning pulley a portion of the thread thereon frictionally contacts the rubber belt 69 which resists the passage of the thread over the tensioning pulley 66. The thread tension occurring between the core and the pulley 66 depends upon the tension of the rubber belt 69 and also upon the amount of lap of the belt upon the tensioning pulley, which determines the area of the thread which contacts the belt and thus the amount of slippage therebetween. The thread tension may therefore be adjusted by adjusting the belt tension or by adjusting the amount of lap of the belt upon the tensioning pulley.

A thread-break indicating device is rigidly attached to the face-plate 14 and comprises a lever 76, Figs. 1 and 3, pivoted at one end, and carrying at its other end the pulley 68. A micro-switch 77 is rigidly attached to the face-plate 14 so that its spring-loaded operating plunger 78 contacts the lever 76 between its ends. The micro-switch is connected in the driving motor circuit so that when the lever 76 is depressed by the tensioned thread passing over the pulley 68, the micro-switch plunger is depressed so that the motor circuit is maintained. Should a thread break occur, the lever 76 is no longer depressed by means of the tensioned thread and the micro-switch is actuated so that the driving motor circuit is interrupted and the machine drive stopped.

Electrical means are also provided for stopping the driving motor when a golf ball core being wound on the rollers 10 reaches a predetermined size. The means comprises an upstanding plunger 79, Fig. 3, rigidly attached to the upper side of the U-shaped member 30, this plunger projecting upwardly through a guide 80 attached to the bottom end of the cylinder 34. The top end of the plunger is provided with an operating pin 81 secured to the end of the plunger by means of a cap 82, the pin being slidable in the cap axially relative to the plunger against the pressure of a spring 83 urging the pin axially outwardly relative to the plunger. The operating plunger 84 of a second micro-switch 85 is located above the operating pin and in axial alignment therewith. The micro-switch is mounted on a bracket 86 which is pivotable on the face-plate 14, movement of the bracket being effected by means of a thumb-screw 87 secured to a pillar 88 and serving to move the bracket so that the micro-switch operating plunger is moved towards or away from the operating pin.

The micro-switch is connected in the motor drive circuit so that the machine will be stopped when its operating plunger is actuated.

By adjustment of the position of the micro-switch it can be made to operate when the concave-profiled rollers are lifted by a golf ball core of any of a range of predetermined sizes.

The operation of the machine which has just been described will now be outlined.

The rubber thread 90 from a reel 91 is passed around the thread-tensioning device, over the pulley 68 and around a core which is placed on and between the cylindrical rollers 10, the concave-profiled rollers 29 being lifted to enable this to be done by depressing the push-button 41. This causes a supply of air to flow from the valve 40, through the pipe 43 to the relief valve 44 to move the shuttle 46 (see Fig. 4) upwardly against the spring 47 until air flows past the end of the shuttle to the outlet 49 and the pipe 50. The air then flows through the port 39 into the cylinder 34 to force the piston upwardly thus lifting the rollers 29. The shuttle in moving upwardly communicates the exhaust port 48 with the port 51 to exhaust the upper part of the cylinder 34. When the push-button 41 is released the relief valve assumes once more the disposition shown in Fig. 4. The machine will commence to operate when a start switch fitted to the face-plate is closed, provided that the micro-switch associated with the thread-break indicating device is depressed by the thread. The cylindrical rollers are simultaneously rotated and axially oscillated so that the golf ball core is subjected during winding to random motion in order that the resulting core may be spherically shaped when wound. During winding, the automatically-operated valve 53 intermittently supplies air to the cylinder 34 through the relief valve 44, which has its elements disposed, as shown in Fig. 4, with the bottom part of the cylinder 34 communicating with the exhaust port 48 through the pipe 50, outlet 49 and the shuttle 46. The air is supplied to the upper part of the cylinder in the manner described so that the concave-profiled rollers 29 are intermittently forced with increased pressure against the core so as to compact the winding as it progresses. When the core reaches a size predetermined by adjustment of the position of the second micro-switch, the latter is actuated by means of the operating pin 81 so that the motor is stopped. The wound core may then be removed after pushing the push-button 41 so as to lift the concave-profiled rollers 29 clear of the wound core.

Having described our invention, what we claim is:

1. A golf ball core winding machine comprising a pair of driven, axially slidable, cylindrical core-supporting rollers spaced side by side on substantially parallel axes, a pair of freely rotatable concave-profiled rollers in spaced relation to each other on axes substantially parallel to

those of the cylindrical rollers, means to press said concave-profiled rollers yieldingly towards said cylindrical rollers and movable away from the cylindrical rollers by increase in diameter of a core on said cylindrical rollers, 5 means for supplying elastic core winding thread under tension to a core on said cylindrical rollers, means for rotating said cylindrical rollers, and an eccentric mechanism for each cylindrical roller to oscillate the rollers axially each of which comprises an eccentric sheave 10 rounded by a strap within which the sheave is rotatable and means for drivably connecting the strap to the cylindrical roller.

2. The golf ball winding machine of claim 1 in which the means for drivably connecting the strap to the cylindrical roller comprises a rocker and an associated linkage comprising an eccentric rod attached at one end to the strap and at the other end to said rocker, a cap 15 within which an end of a shaft carrying a cylindrical roller is freely rotatable and a link connecting said rocker 20 to said cap.

3. The golf ball core winding machine of claim 1, a spring loaded piston and cylinder and an automatically operated air valve for intermittently supplying air under pressure to said cylinder to urge the concave-profiled rollers with increased pressure against a core on said supporting rollers, a manually operated air valve and a shuttle relief valve, said relief valve being connected to the cylinder and automatically-operated air valve so that air may be passed from the automatically-operated valve to 25 the cylinder and being connected to the manually-operated valve and the cylinder so that upon operation of said manually operated valve air may be supplied to said cylinder to move said concave-profiled rollers away from said cylindrical-profiled rollers.
